UNITED STATES PATENT OFFICE.

WILLIAM H. LAMB, OF SAN FRANCISCO, CALIFORNIA.

WATCH-MAKER'S COMBINATION-TOOL.

SPECIFICATION forming part of Letters Patent No. 257,726, dated May 9, 1882.

Application filed October 8, 1881. (No model.)

To all whom it may concern:

Be it known that I, WILLIAM H. LAMB, of the city and county of San Francisco, State of California, have invented a Watch-Maker's Combination-Tool; and I do hereby declare the following to be a full, clear, and exact description thereof.

My invention relates to a tool or device for watch-makers' use; and it consists of a frame having two spring arms passing through it longitudinally and so formed that their sides may be made to approach or separate. These arms serve as a poising-tool for the balance, and also as truing-calipers. Upon one side of the frame is a plate, pivoted at one end to the frame, and having the opposite end movable and capable of being fixed so that one side will make an angle with the side of the frame. Between these sides the roller of the staff may be clamped to be removed. The free end of this pivoted plate is provided with a holding device for the second-hands while they are being broached out or fitted, the whole being intended as a handy tool for different classes of work.

Referring to the accompanying drawings for a more complete explanation of my invention, Figures 1 and 2 are perspective views of my tool. Fig. 3 is a horizontal section taken through the slots in which the poising and truing-arms pass. Fig. 4 is a top view of the clamps for the rollers and the second-hand.

A is a frame, which may be made in any suitable or convenient form; but in the present case I have shown it as composed of a base and two end plates. These end plates have slots B C cut down a short distance from the top to receive the spring-arms D, which pass through them, the slot B being wider than the slot C, and it may have a plate, E, between the sides to prevent the open ends of the springs approaching each other more than is desired. The spring-arms D are formed of a single piece of thin spring-steel, like a watch-spring, or other thin metal. This piece is bent to form a bight at a, and the sides extend forward a short distance, parallel, when they widen out by gradual inclines at b, where they pass through the slot C. Beyond this slot the sides of the springs again become parallel, and continue thus until near the slot B, when they

again widen by gradual inclines d, similar to those at b, and pass through the slots B, after which the sides again become parallel until the ends are reached. The relative positions of the inclines b and d to the slots B and C are such that both will simultaneously enter or leave the slots, and their action will be to move the parallel sides of the arms nearer to or farther from each other. This enables me to adjust the sides to receive the pivots of any wheel which I desire to poise. As the wheel turns freely upon the thin edges of the spring-arms D, the heavier side will settle to the bottom, and it may be taken off until the whole is perfectly poised.

The ends of the arms D have small sockets at e to receive the ends of the pivots of any wheel which may be out of true, and the arms D may be made to approach or recede, as before described, until the pivots are held in the sockets so that the wheel may turn freely.

A jointed arm, F, is pivoted or hinged to one side of the frame A so that its point may be brought close to the side of the rim of the wheel or balance as it revolves, and the point at which it is out of true will thus be easily discovered, so that the wheel or balance can be properly trued up.

A plate, G, lies upon one side of the frame A, and is pivoted to it at one end, I, while the opposite end is free to move back and forward around its pivot.

A bar, H, is fixed to the frame at one side of the plate G, so that when turned upon its pivot-pin the plate may close toward or against this bar and act as a clamp to hold anything which may be placed between the two. The bar and the plate each have small grooves i in their meeting edges, one pair of which serve to hold the roller of the balance, so that the staff may be easily removed when necessary. The other grooves serve to hold the minute-hand while being fitted to the post.

The frame A has a slot, W, cut in it, so that the wheel may have space to lie below the clamp while the roller is held within it.

In order to hold the plate G firmly at any desired point, so as to clamp the article to be held, holes I' are bored in the end of the frame A, and similar holes are bored in the end of the plate G to receive a pin, J, which will enter the holes

which correspond, when the article is properly clamped between the holding-jaws.

The pin J is fixed to a spring-arm, K, which is slotted at the opposite end, so as to fit over the pivot of the plate G, and at the same time to allow it to move enough to bring the pin into line with either of the lines of holes L'.

In order to hold the second-hand while broaching it out to fit its stem I have an arm, L, which projects from one end and forms a part of the plate G. This arm is perforated to receive the socket of the second-hand. Upon the top of the arm are two spring-arms, m and n, the lower one, m, lying flat upon the arm L, while the upper one is arched up in the center. Each of these spring-arms is perforated to correspond with the perforation in the arm L, so that the socket of the hand may pass through the perforations, while the hand itself lies between the arm L and the spring-arm m. When it has been placed the thumb may be pressed upon the convex portion of the upper spring, n, and this will by forcing it down lengthen it out, so that the side of the hole will bind against the socket of the hand above, while the opposite side of the hole below will bind against the other side of the socket, thus holding it firmly while it is being broached out or fitted.

Having thus described my invention, what I claim as new, and desire to secure by Letters Patent, is—

1. The frame, A having the slots B and C

formed in its ends, as shown, in combination with the spring-arms D, having inclines b and d, substantially as and for the purpose herein described. 35

2. The parallel arms D, having the sockets e to receive the pivots of a wheel, and having the converging inclines b and d for adjusting the distance between the arms, in combination with frame A, having slots B and C, substantially as herein described. 40

3. The hinged or pivoted swinging plate G, having grooves i, the bar H, having corresponding grooves oppositely arranged to grooves i, the frame A, having perforations L', and the spring-bar K, with its locking-pin J, the whole constructed to act in combination, as set forth. 45

4. In combination with the frame A, the perforated arm L, perforated spring-arm m, and perforated and arched spring-arm n, arranged for operation substantially as described.

5. A tool consisting of the frame A, slotted, and having the arms D, with their inclines and the sockets e, together with the pivoted clamping-plate G, with its locking-pin, and the perforated arms L m n, substantially as herein described. 55

In witness whereof I hereunto set my hand.

WM. H. LAMB.
